Primary Examiner — Holly Baynham(74) *Attorney, Agent, or Firm* — Jacox, Meckstroth & Jenkins(57) **CLAIM**

The ornamental design for ammunition storage container, as shown and described.

DESCRIPTION

FIG. 1 is an isometric view of an ammunition storage container in accordance with one embodiment;

FIG. 2 is a front elevational view with rear elevational view being identical view of the ammunition storage container shown in FIG. 1;

FIG. 3 is a right elevational view with left elevational view being identical of the ammunition storage container shown in FIG. 1;

FIG. 4 is a top plan view of the ammunition storage container shown in FIG. 1 with the left side being similar thereto;

FIG. 5 is a bottom plan view of another ammunition storage container for receiving the container shown in FIG. 1; and,

FIG. 6 is a bottom perspective view of the ammunition storage container shown in FIG. 1.

The portions shown in broken dashed line are for illustrative purposes and form no part of the claimed design.
